UNITED STATES PATENT OFFICE.

DANIEL WALTER, OF HOVE, ENGLAND.

LOCKING DEVICE FOR CASEMENT-STAYS.

1,148,877.

Specification of Letters Patent.

Patented Aug. 3, 1915.

Application filed November 30, 1914. Serial No. 874,853.

To all whom it may concern:

Be it known that I, DANIEL WALTER, consulting engineer, a subject of the King of Great Britain, of Grosvenor House, New 5 Church Road, Hove, Sussex, England, have invented a new and useful Locking Device for Casement-Stays; and I do hereby declare the following to be a full, clear, and exact description of the invention, such as 10 will enable others skilled in the art to which it appertains to make and use the same.

This invention relates to locking devices for casement stays and has for its object the provision of a device which shall eliminate the use of a key for releasing purposes as has hitherto been usual with devices of this character.

A further object is the provision of a 20 locking device for casement stays which will be simple, comparatively inexpensive in manufacture, efficient and durable in use and a general improvement of the art.

With these and other objects and advantages in view, my invention consists in the novel construction, formation, arrangement and combination of parts to be hereinafter more fully described and claimed and illustrated in the accompanying drawings, in 30 which:—

Figure 1 is a fragmentary view of a casement and frame with the locking device in position. Fig. 2 is a vertical section taken on line A A of Fig. 1. Fig. 3 is a vertical 35 section of a modification. Fig. 4 is a detail of a further modification. Fig. 5 is a vertical section of a further modification.

Referring to Figs. 1 and 2 of the drawings the casement 1 is hinged in the usual 40 manner to the frame 2 and is provided with an arm 3 pivoted at 4 to a bracket 5 so as to be capable of movement in one plane irrespective of the casement.

To retain the casement in the desired position means have to be provided for instantaneously locking the same and which means have also to be so devised that the release from a locked position is attained with equal facility. One form of such a means 45 made in accordance with this invention is shown in Fig. 2 and consists of two concentrically arranged telescopically collapsible tubes or cylinders 8 and 11 both of which are closed at their inner ends. The 50 outer tube 8 is supported by shoulders 9 on and within a base member 6 which is

recessed to receive it and which is firmly secured to the casement frame by screws 10 or other means.

A central screw 11' is provided, passing 60 through the inner closed end of the tube 8 into the casement, to retain the device in position with an allowance at the same time for rotation.

The inner tube or cylinder 11 is slidably 65 mounted within the tube 8 and is provided at its closed end with an interiorly projecting centrally arranged locking pin 12. This pin 12 is adapted to engage in recesses formed within the under surface of the 70 casement arm 3 which is arranged to pass completely through the two concentric tubes and directly over the pin 12 by reason of the corresponding recesses 13 provided.

The inner tube or cylinder 11 with its 75 pin 12 is held in a normally raised position by means of a suitable spring 15 the lower part of which rests upon the closed end of the outer tube 8. When in this raised position the locking pin 12 is forced into engagement with the recesses in the casement arm aforesaid and to release the same therefrom the inner tube 11 is depressed, means, such as a cap 21 being provided to facilitate the 80 operation.

The device represented in Fig. 2 is intended 85 for use with triangular cross section casement arms.

The modified form according to Fig. 3 is precisely similar in operation to the one just 90 described in connection with the previous figure with this difference that the base member 6 is of a box like construction with the object of providing a deeper bearing for the inner end of the outer tube 8. A further difference is in the shape of the corresponding recesses 13 which in this instance 95 are semi-circular to accommodate casement arms of circular section.

The modified form according to Fig. 4 100 relates to the means for rotatively supporting the outer tube 8. In this instance the tube 8 is formed with a downwardly projecting annular flange 18 by which it is supported upon an annular upstanding flange 105 19 formed on the base member 6.

In Fig. 6 is shown a further modified 110 form intended primarily for use with fixed casement arms. According to this form the locking device is secured by means of the outer tube 8 to the casement 1 while the inner tube 11 carrying the locking pin 12 is

suitably slotted to allow for clearing the arm 3 during depression.

It will be seen that the device is applicable equally for curved as for straight casement arms.

What I do claim as my invention and desire to secure by Letters Patent is:—

1. A locking device for casement stays comprising a hollow member, a second member 10 slidable in the first member and directly engageable to actuate same to release position, said members being provided respectively with opposite openings through which a casement stay is adapted to slide, a locking 15 stud carried by the second member, and means for yieldingly holding the second member in position to dispose the locking stud in engaging position with respect to a casement stay.
- 20 2. A locking device for casement stays

comprising a hollow member, a second member slidable in the first member and directly engageable to actuate same to release position, said members being provided respectively with opposite openings through which 25 a casement stay is adapted to slide, a locking stud carried by the second member, and a spring interposed between the inner ends of said members for yieldingly holding the second member in position to dispose the 30 locking stud in engaging position with respect to a casement stay.

In testimony whereof I have signed my name to this specification in the presence of two subscribing witnesses.

DANIEL WALTER.
